CLAIM

The ornamental design for a butterfly impact wrench, as shown and described.

DESCRIPTION

FIG. 1 is a perspective view of a butterfly impact wrench incorporating my design;

FIG. 2 is a left side elevational view thereof;

FIG. 3 is a right side elevational view thereof;

FIG. 4 is a top plan view thereof;

FIG. 5 is a bottom plan view thereof;

FIG. 6 is a front elevational view thereof; and,

FIG. 7 is a rear elevational view thereof.

The phantom lines shown in the drawings indicate environmental structure which form no part of the claimed design.
